R. DU TAILLY.
SASH FASTENER.
APPLICATION FILED APR. 4, 1913.

1,174,836.

Patented Mar. 7, 1916.

UNITED STATES PATENT OFFICE.

ROZARIO DU TAILLY, OF LOUISVILLE, KENTUCKY.

SASH-FASTENER.

1,174,836.

Specification of Letters Patent. Patented Mar. 7, 1916.

Application filed April 4, 1913. Serial No. 758,858.

To all whom it may concern:

Be it known that I, ROZARIO DU TAILLY, a subject of the King of Great Britain, residing at Louisville, in the county of Jefferson and State of Kentucky, have invented 5 new and useful Improvements in Sash-Fasteners, of which the following is a specification.

The present invention relates to improvements in sash fasteners, and particularly 10 that class which embodies means whereby two sashes may be locked in either a closed or a partially open position when it is desired to ventilate the room, and furthermore, 15 to provide a device of this character which, when in locked position, will not depend upon the securing elements for retaining the sashes locked.

With the above objects in view, and others 20 which will appear as the nature of the invention is more fully understood, the improvement resides in the construction, combination and operative arrangement of parts set forth in the following description and falling within the scope of the appended 25 claim.

In the drawing: Figure 1 is a perspective view illustrating the improved lock securing two sashes in a closed position, Fig. 2 30 is a similar view but illustrating the sashes partially opened, Fig. 3 is a vertical longitudinal sectional view through the sashes and through the lock, Fig. 4 is a similar 35 view but illustrating the catch swung to an unlocking position, Fig. 5 is a perspective view of one of the sleeve or socket members which is secured within the upper sash, and Fig. 6 is a similar view of a socket member 40 which may be employed.

Referring now to the drawing in detail, the numeral 1 designates the upper sash of 45 a window, and 2 the lower sash thereof. The vertical stile 3 of the upper sash 1 is provided at suitable spaced intervals with rounded 50 depressions 4 which enter at the outer face of the said stile. The depressions are of a size to snugly receive sleeves or socket members 5, each of said socket members having its outer and open face formed 55 with a rounded flange 6 which is adapted to tightly engage with the outer face of the stile 1, and if desired, the flange 6 may be provided with perforations for the reception of securing elements, but in practice, it has been found further that the sockets 5 engage the wall 60 of the depression 4 with sufficient friction

to retain the said socket within the depression. In the preferred form of the socket, the same has its lower portion provided with a slot 7, the purpose of which will presently 60 be set forth.

Secured to the upper bar or rail 8 of the lower sash 2 is a catch member 9. The catch includes a substantially rectangular base 10 having its corners provided with openings 65 for the reception of securing elements, and the said base is provided adjacent its rear edge and at an equal distance from its center with upstanding lugs 11 between which the elongated arm 12 of the catch proper 70 is pivoted, as at 13. The lower edge of the catch is flat and is adapted to be engaged by a flat spring 14 which has its bowed portion arranged between the lugs 11 and which is secured to the front portion of the base 75 10, as at 15. The arm of the member 12 of the catch has its upper extremity formed with an angular face 16 which, when the catch is thrown to locked position, is received within one of the sockets 5 and which 80 has the lower portion of its bill received within the openings 7 in the bottom wall of the said socket. The juncture of the bill 16 and the arm 12 is rounded or concaved, as at 17, to correspond with the rounded surface 85 at the juncture of the socket and its flange 6, the said rounded portion 17 snugly engaging with the said rounded portion of the sleeve, and it will be noted that should an attempt be made to raise the upper sash 90 1, these portions of the catch and socket will tightly contact, and such an attempt will only serve to slightly raise the outer portion or extremity of the bill 16 from out of the opening 7 of the socket 5. The said bill 16 95 is provided with a convexed upper edge 16' and the said edge abutting firmly with one of the walls of the socket member 5 at a point diametrically opposite to the point of contact of the concaved portion 17 with said 100 socket and by such arrangement affects a binding locking action of the lower sash 2 with respect to the upper sash 1. Should the upper sash be given a downward movement, the upper face of the bill 16 will be 105 contacted, and the arm 12 will be forced tightly against its pivot. It will be noted that as the catch has its bill arranged within the socket, it is absolutely necessary that the base 10 of the catch be secured to the top 110 bar 8 of the sash 2, as the base 10 thereof will prevent a downward movement of the

sash 1, and the bill 16 will prevent an upward movement of the sash 2. It will also be apparent that the catch cannot be unlocked from the exterior of the room. To 5 facilitate the operation of the catch 9, I have provided the arm 12, directly to the rear of its bill 16, with a finger-hold 18.

From the above description, taken in connection with the accompanying drawing, the 10 simplicity of the device, as well as the advantages thereof, will, it is thought, be perfectly apparent to those skilled in the art to which such inventions appertain without further detailed description.

15 Having thus described the invention, what I claim as new is:

In a locking device for the purpose set forth, a socket comprising an annular member having its lower wall slotted longitudinally, a pivoted catch disposed below the 20 socket, said catch including an arm having

its upper end formed with an angularly arranged bill, said bill being formed with an upper convexed edge and a lower concaved edge, means against the lower end of the 25 arm and exerting pressure against said arm to retain the latter at an angle and the convexed and concaved portions of the bill in contact with the walls of the socket and at diametrically opposed points thereof, thereby disposing and retaining the terminal of the bill within the slot of the socket for effecting a permanent locking action of the catch, and a manipulating portion formed integral with and disposed directly in rear 30 of said bill.

35 In testimony whereof I affix my signature in presence of two witnesses.

ROZARIO DU TAILLY.
